CARTON OPENING AND FILLING MACHINE

Application filed September 27, 1928. Serial No. 308,801.

This invention relates to machines for opening, filling, closing and sealing cartons supplied in flattened or collapsed form. It has for one object the provision of mechanism by which these successive operations may be performed upon the cartons while the latter are moving continuously through the machine, thus enabling higher speeds to be used than if it were necessary to interrupt the travel of the cartons periodically opposite different operating mechanisms. It has for a further object the provision of mechanism for giving to a collapsed carton a preliminary opening serving to break the rigidity of its creases and to give it a natural tendency to open in the desired manner. It has for a further object the provision of feeding mechanism for the collapsed cartons which will not deliver a carton unless there is an article in position to be inserted into it.

General description

The mechanism which we have devised for the accomplishment of these objects will be briefly described without reference to the drawings, in order to present the machine in its entirety before considering its details. The cartons are held in collapsed condition upon opposed ledges at the bottom of a vertical magazine from which they are delivered one at a time by a flat blade first entering between the walls of the carton and then moving downwardly to snap the carton through the ledges. This snap breaks the rigidity of the folds enough so that the cartons may be opened with uniformity by mechanism acting after the carton is released by the blade. The blade withdraws from the carton, depositing it upon guides along which it is moved by feeding arms into a pocket of a continuously moving conveyer.

Gradually closing as the conveyer continues its travel, the walls of these pockets press on opposite corners of the carton to cause it to open. As soon as the carton is fully opened and seated in the pocket, its rear flap on one side is folded and an article is pushed in from a continuously moving adjacent conveyer. All flaps but the upper one on each side are then folded, adhesive is applied to

these flaps, the upper flaps are folded, and the carton is ejected between belts which hold the flaps until the adhesive has had sufficient time to set.

In the embodiment of the invention which 55 we have constructed for commercial use, the continuously moving article conveyer comes from the delivery end of a wrapping machine operating to group a stack of articles such as cookies and to wrap them into a hermetically sealed package. In case a wrapped package is not delivered in proper sequence by this machine, we have provided a feeler-controlled mechanism for raising the carton magazine clear of the blade path so that no 60 65 carton will be fed from it.

The drawings

Referring now to the drawings for a detailed explanation of the invention:

Fig. 1 is a side elevation of the machine; 70
Fig. 2 is an elevation taken from the left in Fig. 1;

Figs. 3 and 4 form together a top plan of the machine;

Fig. 5 is a section on line 5—5 of Fig. 4 75 with the glue pot removed;

Fig. 6 is a detail of the gluing device taken from the right in Fig. 5 with certain parts broken away;

Fig. 7 is a detail similar to a portion of Fig. 2 but showing the carton feeding blade in a different position of operation;

Fig. 8 is a section on line 8—8 of Fig. 2, illustrating the normal operation of the carton feeding mechanism as the carton feeding blade is about to enter the magazine; 85

Fig. 9 is a similar view showing the position of the parts with the carton feeding blade withdrawing from the magazine;

Fig. 10 is a view similar to Fig. 8 but showing the lifting of the magazine resulting from the absence of an article;

Fig. 11 is a detail of the carton conveyer; 90
Figs. 12 to 16, inclusive, are details showing the action of the conveyer members in opening a carton;

Figs. 17 to 19, inclusive, are details showing the manner in which a filled and sealed carton is ejected from the conveyer;

Fig. 20 is a view of a collapsed carton;

Figs. 21 to 26, inclusive, are perspective details showing successive steps in the closing and closing of the carton;

Fig. 28 is an end view of a carton about to have the last flap folded and to enter between the delivery belts;

10 Fig. 29 is a detail view of a modification;

Fig. 30 is a similar view of a still further modification; and

Fig. 31 is a view of parts shown in Fig. 30 but in a different position of operation.

15 *Carton feeding mechanism (Figs. 1, 2, 3, 7, 8, 9, and 10)*

The cartons *a* in the collapsed and tightly creased state in which they are delivered 20 from the carton-making machine are stacked in a magazine in the position shown in Fig. 20, in which the two short flaps *b* and *d* at one end and the short flaps *b'* and *d'* at the other end are lowermost. The long flaps 25 *c*, *e*, and *c'*, *e'* are on top. Preferably, in order to make folding easier and the package neater, flaps *d*, *e* and *d'*, *e'* are made narrower than the two remaining flaps at each end.

30 The magazine for holding the stack of collapsed cartons is formed by four corner angle pieces 30 held together by exterior bands 31 and 32. Ledges 33 extend lengthwise of the cartons and serve to support the stack of 35 cartons resting upon them. In order to permit the magazine to have a slight vertical movement for stopping the feed of cartons whenever there is no article presented for packaging, the band 32 is provided with 40 bosses 34 (Fig. 8) through which pass rods 35 held firmly in place by set screws 36 (Fig. 2). The rods 35 are slidably mounted in guides 37 formed in the upper portion of a bracket 38 arising from the main frame 45. The mechanism for reciprocating the rods when no article is present will be considered later. For present purposes, the rods and the magazine can be considered as stationary.

50 Mounted upon the base 39 at one side of the machine is a bracket 40 (Fig. 2) in which is journaled a shaft 41 driven continuously by means to be described. Spaced from this shaft is a second shaft 42 journaled in a member 43 pivoted at 44 to the bracket and adjustable for chain tightening purposes by a set screw 45 threaded through member 43 and bearing against the bracket 40. Shafts 41 and 42 carry sprockets 46 and 47 around

55 which passes a chain 48 traveling continuously in the direction of the arrow in Fig. 7 during the operation of the machine.

Spaced horizontally from each other on the bracket 40 are pivots 50 (Figs. 2 and 7) 60 each bearing a bell crank 51. The two bell

cranks have parallel arms connected together by a link 52. The other arm of each bell crank is provided with a pivoted holder 53 in which is fixed a rod 54. The link 52 and the rod 54 form with the bell cranks a parallel motion mechanism whereby the rod may be raised and lowered in a constantly horizontal position. A spring 55 strained between one of the bell cranks and a pin 56 fixed upon the bracket 40 counterbalances 75 the weight of the parts supported by the linkage.

Freely movable upon the rod 54 is a slide 57 to which is fixed the carton feeding blade 58. An arm 59 depending from the slide carries a pivot 60 upon which freely swings a yoke 61 attached to the chain 48 by pins 62. As the chain rotates the yoke will be carried steadily with it in a continuous path. In Fig. 2 the yoke is traveling to the right along the lower reach of the chain, drawing the slide 57 with it. As the portion of the chain to which the yoke is attached passes around the right-hand sprocket, the yoke will be drawn upwardly, causing the rod 54 and the slide 57 to rise. On the reverse motion given to the slide as the yoke moves along the upper reach of the chain, the pivot 60 will be below the yoke, as shown in Fig. 7, rather than above it, as shown in Fig. 2. In passing around the left-hand sprocket, the yoke will again draw the slide downwardly against the smooth pull of the spring 55.

The effect of this portion of the mechanism is to cause the blade 58 to be moved into the side of the magazine as shown in Fig. 7, lowered while in the magazine, and retracted while in its lowered position. As it enters the magazine, the front of the blade, which is preferably beveled on its bottom as shown, engages the lower side of the long end flaps of the lowermost carton. It will be remembered that the cartons are stacked in the magazine with their long flaps on top. The blade is set so that at the time when it strikes the long flaps of the bottom carton, it is just finishing its vertical movement and just starting its horizontal movement, taking for the moment a motion slanting upwardly towards the stack of cartons. This motion relieves the weight on the bottom wall of the lowermost carton, seats the blade firmly against the upper wall of the carton, and assists in causing the tapered end of the blade to enter between the upper and lower carton walls.

After this momentary slanting travel, the blade moves horizontally into the bottom carton, spreading its walls somewhat. It then descends with the carton, which has to bend considerably adjacent its edges in order to get by the ledges 33. The blade then withdraws from the magazine and from the carton, which is held by the sides of angle members 30 acting during this movement of the blade as a carton stripping abutment, and de-

positis the carton on parallel guideways 63 extending from beneath the magazine to the right thereof as viewed in Fig. 1.

The opening of the collapsed carton, thus given, is not sufficient to cause any great permanent change of shape, the carton dropping upon the guideways with much the same flattened appearance as when it was placed in the magazine. The rigidity of the creases, however, has been broken, and the carton can thereafter be opened merely by pressing against its opposite edges. Without the preliminary opening, an attempt to apply pressure against the opposite edges might result, in a certain proportion of the cases, in buckling both carton walls in the same direction rather than in opening the carton.

Carton opening conveyer (Figs. 1, 3 and 11 to 19)

After having been dropped by the blades 58, the cartons are successively pushed over the surface of the guideways 63 by oscillating fingers 65 into the pockets of a continuously running conveyer chain serving both to open the cartons and to carry them past the mechanism which operates to fill them and to close and seal their flaps. The conveyer chain which we have developed for this purpose is entirely self-contained, operating to open and close the pockets and to eject the cartons therefrom by parts rigidly connected to the conveyer links, no cams or other moving parts being employed.

Shafts 70 and 71 are journaled in standards 72 and 73 arising from the main frame 39, and carry sprockets 74 and 75 fixed to them. Over these sprockets runs a conveyer chain composed of rollers 76 centrally mounted on pintles 77 carried at their ends in repeated sequences of links 78, 79 and 80 (Fig. 11). The rollers fit between the teeth of the sprockets, while the links overlie the ends of the sprockets and thus hold the chains in position. It may be mentioned that in order to avoid vibrations in the chain and to keep its upper run as constant in elevation as possible, it is preferred to mount the two sprockets as shown in Fig. 11 with a tooth of one and a valley of the other uppermost at a given instant. During the straight travel of the chain between the sprockets the rollers 76 travel over a support 67.

Links 78 bear pushers 81 (Fig. 11) having overhanging hook portions 82 adapted to grasp a rear edge of a carton. Links 79 are idle, serving merely as parts of the chain. Links 80 bear two devices, a front member 83 having a carton seating ledge 84, and an ejector finger 85. The pushers 81 and the front members 83 are in line with the links (see Fig. 3), and are arranged to pass between the two guideways 63. The ejectors 85 are outside the links and pass directly underneath the guideways.

The operation of the conveyer in receiving and opening up a carton is shown in Figs. 12 to 16. In Fig. 12, the pocket is shown just before a collapsed carton is delivered to it by the fingers 65, which occurs as indicated in about the position of Fig. 13. As the chain continues to move, the front member 83, which is carried by the horizontally moving link 80, maintains its upright position. Pusher 81, outstanding from the second link to the rear, is still rotating with the shaft 70 as a center as its supporting link passes around the pulley. The rear edge of the carton is gradually raised up from the guideways 63, sliding over the slanting surface of the pusher, and at a position just after that shown in Fig. 14 is engaged by the hook 82. Further approach of the link 78 towards the horizontal causes the two opposite corners of the carton to be pressed together as in Fig. 15. Complete squaring of the carton occurs as soon as the three links 78, 79, and 80 are horizontal. As shown in Fig. 16, the opened carton is firmly grasped by the pusher 81 and the front member 83, being held in this position while it is carried by the conveyer through the filling and sealing mechanisms.

The conveyer also acts automatically and solely through the operation of parts rigidly attached to its links to open the pocket and to eject the carton after it has been filled and closed. The ejectors 85 are mounted on links 80 so that they lie below the plane of the cartons as long as the chain continues its straight travel. When one of the links 80 starts to pass around the sprocket at the right as viewed in Fig. 11, the front member 83 is lowered (Fig. 17), disengaging the carton and permitting it to be carried by the pusher 81 along guideways 86. At the same time, the ejector finger 85 is raised and swung in such an arc that the carton is pushed clear of the hook 82 and into certain delivery and flap pressing devices which will be described later. The successive stages in this ejecting action will be apparent from Figs. 17 to 19.

Flap closing devices (Figs. 1, 3, 4, 5, 6 and 20 to 29)

As the opened carton is being carried along in a pocket of the conveyer, its end flaps are acted upon by various folding devices which will now be described. As soon as the carton has been completely opened, its short rear flap *b* at that side of the machine from which the blade 58 operates is acted upon by a swinging folder 90 carried by the arm 91 of a rock shaft 92. Immediately thereafter, the front flap *c* runs under the end of a stationary rail 93 and is thereby folded over the previously folded rear flap. The rail 93 is long enough so that it holds the flaps in position until the bottom flap folder operates, and also serves as a backing to prevent movement of

130

the carton when the article to be packaged is pushed into it.

The carton is at this point charged with a wrapped article by means which will be described later, the charging, as well as the folding operations, taking place while the carton is in continuous motion. When the carton has passed beyond the charging apparatus, its rear flap b' on the second end 10 (the end into which the article is inserted) is brought within range of an oscillating folder 94 similar to the rear closer 90, and carried upon an arm 95 mounted on a rock shaft 96. Shaft 92 has an arm 97, and shaft 96 an arm 98, connected together by a link 99, so that the two folders swing together although they are, to use an electrical analogy, ninety degrees out of phase. This is for the reason that the folder 94 operates on a carton after it 15 has moved from the range of folder 90, and at a time when the folder 90 has to be out of the way of a succeeding carton.

In order to oscillate the two folders periodically in timed relation to the remainder of the mechanism, shaft 96 is provided with a second arm 100 joined by a link 101 with a constantly rotating crank 102 on a shaft 103. At each revolution of the shaft 103, the folders 90 and 94 will be actuated successively. Shaft 103 carries a bevel gear 104 (Fig. 3) meshing with a similar gear 105 on a sleeve 106 loosely mounted on a transverse shaft 107.

As soon as the carton has passed the second rear folder, its long front flap c' strikes a stationary plate 108 which folds it back over the short rear flap b' and then holds both flaps until the folding of the bottom flap has progressed sufficiently to make the release of the front and rear flaps safe. The bottom flaps d and d' are engaged simultaneously by stationary plow folders 109 and 110, both being preferably made integral with the main frame of the gluing device at their own side of the conveyer, and folder 110 being preferably integral with plate 108. Rail 93 and plate 108 are preferably cut away sharply at 111 and 112, respectively (Figs. 25 and 26) so that the bottom flaps d and d' may swing bodily about their pivotal creases without interference.

55 The upper flaps e and e' are now the only ones projecting from the carton ends. They receive a dab of adhesive from a gluing device to be described below, and are then folded down upon the other flaps by folders 113 mounted just beyond the gluing apparatus.

60 Article inserting mechanism (Figs. 1, 2, 3, 4, 22, and 23)

The present machine has been designed to receive wrapped articles directly from a wrapping machine, and to that end a conveyor is provided which is preferably driven

from the latter mechanism. This conveyer comprises a pair of spaced chains 115 (Fig. 3) driven from sprockets (not shown) at the wrapping machine and guided by sprockets 116 freely rotatable on the shaft 107. The 70 chains run in slots 117 formed in a stationary shelf 118, upon which the articles slide under the influence of curved pusher plates 119 attached to spaced links on the chain.

Pivoted at 120 (Fig. 4) to a stationary 75 part of the machine is an arm 121 having a pusher head 122 (Fig. 3) adjustably clamped to it by a bolt 123. A link 124 (Fig. 4) is pivoted to the arm 121 at 125, and at 126 to an arm 127 projecting from the shaft 96. 80 The pusher is thus caused to swing in synchronism with the rear flap folders on an arc which extends across the article conveyer to the open side of a carton on the carton conveyer. As the pusher swings to- 85 wards a carton, its speed on this arc is such that the component of motion parallel to the conveyers corresponds roughly to the linear speed of the conveyers, so that the pusher maintains its engagement with the rear end 90 of an article while sweeping it sideways from one of the plates 119 into the open end of a moving carton (Fig. 22). Immediately returning from this position, the head 122 95 passes across the article conveyer in the rear of that plate from the front of which it had just removed an article.

Gluing mechanism (Figs. 1, 4, 5, 6, and 27)

The mechanisms for applying glue or other adhesive such as sodium silicate to the outstanding upper flaps e and e' are in duplicate on the two sides of the machine, and a description of one only will be given. Each device comprises a dauber which is alternately lowered into a glue pot and raised to contact with a carton flap as it comes by in its continuous movement. Since the flap is moving, the dauber is also moved longitudinally of the carton conveyer during the short time it is in contact with the flap. 100 105 110

The glue pot 130 (Fig. 6) is fixed upon the standards 73 which support the shaft 71, and has across its top a plate 131 adapted to overlie the flap *e* and to hold it in position. The glue dauber 132, bearing a glue applying die 133 of suitable form (here shown as U-shaped) is carried upon an arm 134 fast upon a sleeve 135 freely rotatable upon a crank pin 136 (Figs. 5 and 6). A second arm 137, also fixed upon the sleeve 135, is forked at its lower end to embrace a square sleeve 138 freely turnable on the shaft 71 to guide the dauber arm 134 as the crank pin is rotated. The crank pin is carried upon a crank arm 139 rotatable on a pivot shaft 140. A gear 141 on the crank arm meshes with an idler 142, which in turn meshes with a gear 143 on the conveyer shaft 71. 115 120 125 130

As the conveyer shaft 71 is constantly rotated by the conveyer chains, the crank arm 139 will also be constantly rotated. In each cycle, the dauber will be lowered into the glue pot and then raised in timed relation to the conveyer, so that it meets a carton flap being fed under the plate 131. During the upper part of its motion, the dauber partakes of the rotative movement of the crank pin, moving for a short distance at the same rate as the flap. In order to avoid the application of glue to the bottom surface of plate 131 if no carton is present, the plate is preferably apertured as at 144 (Fig. 4) in substantially the same pattern as the die 133, but in larger area.

As a matter of convenience in filling and draining the glue pot, a spout 145 is pivoted at 146 at one side of the pot. The pivot is hollow and communicates both with the pot and with the spout. When the spout is up, the adhesive poured into it will fill the glue pot, the sides of the spout being above the liquid level. If it is desired to drain the glue pot, the spout is swung downwardly about its pivot, which is below the lowest point in the pot, so that all adhesive will run out.

Delivery mechanism (Figs. 1 and 4)

After the top-flaps of the carton have been glued, the carton is ejected from the conveyor pocket by the fingers 85 operating in the manner described above. This pushes the carton flap past the folders 113, and moves the carton between intermittently movable delivery belts 150. These belts run over idle pulleys 151 and driven pulleys 152. One of the belts passes over a fixed abutment 153 and the other over an abutment 154 pressed by springs 155 against the belt. By this means the end flaps of the carton are subjected to a yielding pressure which holds the glued flaps until the adhesive has become set, and slight inequalities in the lengths of the packages are accommodated. As they are being carried intermittently by the belts, the cartons slide over a delivery table 156 which extends beyond the belts so that the cartons are stacked in a convenient position for being removed by the operator.

For rotating the pulleys 152 intermittently, they are each provided with a ratchet 157 acted on by a pawl 158 pivoted on a pawl carrier 159 and pressed towards the ratchet by a spring 160. One of the pawl carriers is provided with an arm 161 joined by a link 162 with an arm 163 projecting from the shaft 96 which operates the second rear folder 94. A link 164 joining the two pawl carriers causes them both to move simultaneously.

Carton feed control (Figs. 1, 2, 3, 8, 9 and 10)

In order to avoid waste, the present machine is provided with control mechanism

whereby no carton will be fed from the magazine unless a wrapped article is present to be pushed into it. Instead of stopping the movement of the carton feeding parts, the machine prevents the feeding of a carton by causing a slight vertical movement of the carton magazine, just sufficient to cause the carton feeding blade 58 to pass under the lowermost collapsed carton in the magazine rather than between the carton walls. The mounting of the magazine for vertical sliding movement on rods 35 has been described above. The mechanism for causing this motion will now be considered.

Power for moving the magazine is derived from the oscillating mechanism for the fingers 65 which sweep the carton into the conveyer pockets. These fingers are fixed to a rock shaft 170 extending across the machine and are oscillated by a crank 171 (Fig. 1) carried by a shaft 172 and joined to one of the fingers 65 by a connecting rod 173. The shaft 172 bears a sprocket 174 around which passes a chain 175 driven from a suitable sprocket (not shown) on the wrapping machine with which the present machine is associated. A chain tightening pulley 176 for maintaining this chain under proper operating conditions is shown in Fig. 1.

Through a disk 177 (Figs. 2 and 8) fixed to the shaft 170 extends a pin 178 which in each cycle of the machine oscillates through an arc best shown by a comparison of Figs. 8 and 9. In the normal operation of the machine, this pin performs no function. When, however, no article is present in the article conveyer, the forked end 179 of a lever 180 is shifted to a position directly above the pin when this is in its lowermost position. The lever is pivoted at 181 to a bracket 182 fixed to the rods 35 which carry the magazine, and is concaved at 183 to fit the pin. As the pin moves through its arc, it will, with the lever 180 in the position of Fig. 9, engage the lower end thereof and move it, together with the bracket 182, the rods 35, and the magazine, a sufficient vertical distance so that the lowermost carton is above the path of the blade 58.

To rock the lever 180 whenever an article is not in place in the conveyer, its upper end is provided with a smooth contact surface 184 against which bears a similar contact surface 185 on a lever 186 fixed on a shaft 187 journaled in a bracket 188 projecting from the carton magazine. A feeler 189 is fastened to the end of this lever and projects into the path of the end of an article being pushed along the shelf 118 by a pusher plate 119. If an article is present, as in Fig. 8, the levers 180 and 186 will be rocked to bring the end 179 of the former out of the path of the pin 178. If no article is present, this motion does not take place, and the magazine is lifted as shown in Figs. 9 and 10.

In order to relieve the parts from the full

weight of the magazine, the latter is partially counterbalanced by springs 190 stretched between the bracket 182 and the fixed bracket 38. A spring 191, strained between the lever 180 and a pin 192 on the bracket 182, partially counterbalances the weight of the various lever mechanisms to render their movement by the article easier.

Main gearing (Figs. 1 and 3)

10 The main drive of the machine is derived from the wrapping machine through chain 175, the article conveyer chain 115 being separately driven, also from the wrapping machine. Shaft 172 is driven by chain 175, and drives directly the fingers 65 and the magazine raising mechanism. A gear 193 on shaft 172 meshes with a gear 194 on shaft 70, which drives the carton conveyer and 15 through it the gluing device. Gear 194 also meshes with a smaller gear 195 on the sleeve 106 which has been described as driving the rear flap folders, the article charging plunger 122, and the intermittent delivery conveyer. A bevel gear 196 on the sleeve 106 meshes with a gear 197 on the shaft 41 which causes motion of the carton opening blade 58. All the mechanisms are by this gearing 20 interconnected so that they operate in timed sequence to each other and to the wrapping machine.

Summary of operation

Assuming the carton magazine to be full 35 of collapsed cartons and a constant succession of wrapped articles to be supplied by the chain pushers 119, the machine operates in the manner which will now be briefly summarized. The blade 58 moves into the carton magazine, at first in a slightly upward direction and then horizontally until it has passed well between the walls of the lowermost collapsed carton. It then moves downwardly, snapping the carton past the opposed ledges 33 and thereby effectively 40 breaking the rigidity of the creases. As the blade withdraws from the magazine, the carton is held back by the end walls 30 until it is entirely released and drops onto the 45 guideways 63.

Fingers 65 sweep the carton along these guideways and into an open pocket of the conveyer chain, as shown in Fig. 13. As the conveyer moves along continuously, flap 55 *b* is bent inwardly by folder 90 and flap *c* by folder 93. At substantially the same time, the wrapped article *s* is pushed into the open end of the carton by the swinging pusher 122. Flap *b'* is then closed by folder 60 94 and flap *c'* by the plate 108.

The remaining flaps are handled simultaneously at both ends of the carton. The two bottom flaps *d* and *d'* are turned upwardly 65 by the plows 109 and 110, the outstanding upper flaps *e* and *e'* receive a dab of ad-

hesive from the gluing device, and these latter flaps are finally turned downwardly against the others by folders 113. The action of the conveyer pockets illustrated in Figs. 17 to 19, then ejects the closed and sealed carton between the delivery belts 150.

Modified delivery mechanisms (Figs. 29, 30, and 31)

The mechanism as described above will 75 operate satisfactorily on most types of cartons, and is desirable by reason of its compactness and simplicity. In this mechanism the last flap is not folded down by the folder 113 until the carton is just being released by the opening conveyer pocket, and where the carton blanks have especial resilience the glued carton may spring back slightly out of square before it is gripped by the belts 150. In order to avoid this difficulty we 80 have devised two modifications, one operating by holding the carton firmly in the conveyer pocket until the final flap is folded and the glue given a slight period to set, and the other operating through a special ejector 85 which presses on the carton in a direction resisting any tendency to collapse.

The first modification is illustrated in Fig. 29, and differs essentially from the machine as described only in employing a slightly 90 lengthened conveyer. In the modified form the conveyer chain, instead of passing around a sprocket 75 on shaft 71, passes around a similar sprocket 200 on a shaft 201 suitably geared to the shaft 71. The belts 150 are replaced by belts 202 constructed similarly to belts 150 but spaced further from the shaft 71. This provides a space between the belts and the folder 113 through which the carton passes after the folding of the final flap. Rails 203, which may be spring pressed if desired, hold the flaps until the cartons are pushed by ejectors 85 between the belts 202.

The second suggested modification leaves 100 the belts 150 in their original position, but omits the ejectors 85 from the conveyer. Their place is taken by a pair of fingers 205 mounted on a shaft 206 suitably journaled in the machine frame. A gear 207 on this shaft 105 meshes with the gear 141 of one of the gluing devices, being of double the number of teeth so that the shaft will revolve one-half a revolution during each cycle of the machine. The ends 208 of the arms are curved so that they bear upon the upper rear corner of the carton as shown in Fig. 31. The pressure of the ejector arms against this corner of the carton effectively counteracts any tendency 110 of the carton to collapse, and preserves the squareness of the carton until it is received between the belts 150.

Other modifications of the structure described will doubtless suggest themselves to those skilled in the art, and we do not intend 115

to limit ourselves to the details of mechanism shown.

We claim:

1. A device for setting up collapsed cartons comprising a carton magazine having opposed ledges for supporting a stack of collapsed cartons each having longer flaps on its upper flattened sides than on its lower sides, a blade, and means for moving the blade laterally into the magazine first in a slanting direction to press against the upper flaps, then into the carton parallel to its walls to separate them, and then past the ledges to force the carton between them and break the rigidity of its creases. 70
2. A device for setting up collapsed cartons comprising a carton magazine having opposed ledges for supporting a stack of collapsed cartons, a blade, means for moving the blade so as to project it into the lowermost carton in the magazine and to remove it therefrom, means for completing the opening of the carton, means for carrying articles into position to be inserted into the opened carton, and means actuated by the absence of an article in said carrying means for rendering the blade inoperative to remove the lowermost carton from the magazine. 75
3. A device for setting up collapsed cartons comprising a vertically movable carton magazine having opposed ledges for supporting a stack of collapsed cartons, a blade, means for moving the blade to cause it to enter the lowermost carton in the magazine and to remove it therefrom, means for completing the opening of the carton, means for carrying articles into position to be inserted into the opened carton, and means actuated by the absence of an article in said carrying means for bodily moving the magazine vertically to remove the lowermost carton from the path of the blade. 80
4. A device for setting up collapsed cartons which comprises opposed ledges for supporting a carton, a blade, means for moving the blade first into the carton, then past the ledges to break the rigidity of the creases of the carton, and then out of the carton to completely release it, and a carton opening pocket adapted to exert pressure on opposite corners of the released and recollapsed carton to open it. 85
5. A device for setting up collapsed cartons which comprises opposed ledges for supporting a carton, a blade, means for moving the blade first into the carton, then past the ledges to break the rigidity of the creases of the carton, and then out of the carton to completely release it, a guideway upon which the release and recollapsed carton may rest, a carton conveyer having devices positionable adjacent the guideway for exerting pressure on opposite edges of the recollapsed carton to open it, and means for feeding a recollapsed carton along the guideway to the conveyer. 90
6. A device for setting up collapsed cartons comprising a pair of sprockets, a linked conveyer chain passing around the sprockets, and pocket members rigidly connected to the chain links and moved into and out of their pocket forming position solely by the motion of the links relatively one to another during the motion of the chain. 95
7. A device for setting up collapsed cartons comprising a pair of sprockets, a linked conveyer chain passing around the sprockets, and pairs of pocket forming members rigidly connected to the chain links, the two members of each pair having opposed carton corner engaging surfaces and being connected to different chain links so as to partake of the movement of the latter relatively one to another during the motion of the chain. 100
8. A device for setting up collapsed cartons comprising a pair of sprockets, a linked conveyer chain passing around the sprockets, pairs of pocket forming members rigidly connected to the chain links, the two members of each pair having opposed carton corner engaging surfaces and being connected to different chain links so as to partake of the movement of the latter relatively one to another during the motion of the chain, and a series of ejector fingers rigidly connected to certain of the chain links. 105
9. A device for setting up collapsed cartons comprising a conveyer chain having a sequence of links pivoted together, and cooperating pocket members rigidly secured to remote links. 110
10. A device for setting up collapsed cartons comprising a conveyer chain having a sequence of links pivoted together, a pocket member having a hooked end and rigidly connected to one link, and a second pocket member having a carton-supporting ledge and rigidly connected to a link spaced at least one link from the first-named link. 115
11. A device for setting up collapsed cartons comprising a conveyer chain having a sequence of links pivoted together, a pocket member rigidly connected to one link, a second pocket member rigidly connected to a link remote from the first link, and an ejector finger rigidly connected to the second link. 120
12. A device for setting up collapsed cartons comprising a conveyer chain having a sequence of links pivoted together, a pocket member having a hooked end and rigidly connected to one link, a second pocket member having a carton-supporting ledge and rigidly connected to a link remote from the first link, and an ejector finger rigidly connected to the second link. 125
13. A device for setting up collapsed cartons comprising a pair of continuously rotating spaced sprockets, a conveyer chain running over said sprockets and having a sequence of links pivoted together, a pocket member having a hooked end and rigidly con- 130

- nected to one link, and a second pocket member having a carton-supporting ledge and rigidly connected to a link remote from the first link, the two pocket members presenting 5 parallel carton-grasping walls when the links are in line but separating to open up the pocket when one of the links is deflected by passing around a sprocket.
14. A device for setting up collapsed car- 10 tons comprising a pair of continuously rotat- ing spaced sprockets, a conveyer chain running over said sprockets and having a se- quence of links pivoted together, a pocket member having a hooked end and rigidly connected to one link, and a second pocket member having a carton-supporting ledge and rigidly connected to a link remote from the first link, the two pocket members presenting 15 parallel carton-grasping walls when the links are in line but separating to open up the pocket when one of the links is deflected by passing around a sprocket, and an ejector finger rigidly connected to the second named link and projectable into the carton path by 20 the passage of the second link onto a sprocket.
15. A device for closing the flaps of car- 25 tons comprising a continuously moving carton conveyer, a glue pot adjacent the path of the conveyer, a reciprocable glue dauber movable into and out of the glue pot, means for imparting to the glue dauber when raised from the glue pot a motion in the direction of movement of the conveyer, and means for folding the glued flap.
16. A device for closing the flaps of car- 30 tons comprising a continuously moving carton conveyer, a glue pot adjacent the path of the conveyer, a reciprocable glue dauber movable into and out of the glue pot, and means for imparting to the glue dauber when raised from the glue pot a motion in the direction of movement of the conveyer, a plate 35 for guiding a carton flap into adjacency with the dauber, and means for folding the glued flap.
17. A device for closing the flaps of car- 40 tons comprising a continuously moving carton conveyer, a glue pot adjacent the path of the conveyer, a reciprocable glue dauber movable into and out of the glue pot, and means for imparting to the glue dauber when raised from the glue pot a motion in the direction of movement of the conveyer, a plate 45 for guiding a carton flap into adjacency with the dauber, said plate being perforated to avoid contact with the dauber in the absence of a carton flap, and means for folding the glued flap.
18. A device for filling and closing car- 50 tons comprising a continuously moving con- 55veyor provided with carton holding pockets, a second conveyor having a portion of its travel adjacent the first and continuously moving at the same speed, said second conveyor having a series of members thereon for carrying a succession of articles in regis- 60 try with the pockets of the first conveyor, a pusher movable completely across the second conveyor in front of one of the advancing members to sweep an article into a carton carried by the first conveyor, and back com- 65 pletely across the second conveyor in the rear of said member, all during the continuous movement of both conveyors, and means adjacent the first conveyor for folding the 70 remaining flaps of the cartons carried thereby.
19. A carton closing conveyor having means for carrying a succession of cartons with their flaps open, an oscillating folder 75 at one side of the conveyor movable to close one rear flap of a carton, means located at a subsequent point of the travel of the con- 80 veyor and on the opposite side thereof for introducing an article into the carton, a sec- 85 ond oscillating folder located at the second side of the conveyor at a still further point in its travel and positively connected to the first in such a manner that one of the folders is always operative while the other is inoper- 90 ative, and means for closing the remaining flaps of the cartons.
20. A device for setting up collapsed car- 95 tons comprising a carton magazine having opposed ledges for supporting a stack of cartons, a blade, mechanism for moving the blade first into the lowermost carton in the stack, then past the ledges to draw the carton be- 100 tween them and thereby open the carton part- way to its squared up form, and then out of the carton, and an abutment positioned to re- 105 strain the carton from moving with the blade during the last-named motion whereby the carton is freed from the blade and permitted to reassume substantially its original flat- tened form but with the rigidity of its creases broken.
21. A device for setting up collapsed car- 110 tons comprising a plurality of guides defin- 115 ing a magazine for a stack of cartons and ex- tending partway across the ends to the car- tons to determine their endwise position, ledges mounted at an intermediate point of the guides and determining the limit of bodily movement of the stack of cartons, and a 120 blade constrained for movement in a path whereby it enters between the guides and be- 125 tween the walls of the carton immediately supported by the ledges, then moves past the ledges to carry that carton beyond the ledges, and then passes out between the guides where- 130 by the carton is freed.
22. A device for setting up collapsed car- 125 tons which comprises means for opening a carton partway to its squared up form and then completely releasing it so that at reas- 130 sumes substantially its original flattened form but with the rigidity of its creases broken, and means for opening up the released car- ton.

23. A device for setting up collapsed cartons which comprises opposed ledges for supporting a carton, a blade, means for moving the blade first into the carton, then past the ledges to draw the carton between them and thereby open the carton partway to its squared up form, and then out of the carton to release it completely and thereby permit it to reassume substantially its original flattened form but with the rigidity of its creases broken, and means for opening up the released carton.

5 24. A carton handling apparatus comprising a continuously moving conveyor, means for delivering collapsed cartons successively to the moving conveyor in timed relation therewith, and means carried wholly by the conveyor for opening up the collapsed cartons.

10 25. A carton handling apparatus comprising a continuously moving conveyor, means for delivering collapsed cartons successively to the moving conveyor in timed relation therewith, means carried wholly by the conveyor for opening up the collapsed cartons, and devices positioned alongside the conveyor for closing the carton flaps and inserting articles in the conveyor during the movement 25 of the latter.

15 30. In testimony whereof we have affixed our signatures.

ELMER L. SMITH.
FREDERIC B. FULLER.
